US0D1016377S

(12) **United States Design Patent** (10) **Patent No.:** **US D1,016,377 S**
(45) **Date of Patent:** **** Feb. 27, 2024**

(54) **LAMP HOUSING**

(71) Applicant: **SAVANT TECHNOLOGIES LLC**,
Cleveland, OH (US)

(72) Inventors: **Zhe Wang**, Shanghai (CN); **Li Jiang**,
Shanghai (CN); **Jing Chen**, Shanghai
(CN); **Hai Huang**, Shanghai (CN); **Jie
Gao**, Shanghai (CN); **Kun Xiao**,
Shanghai (CN); **Jiachen Yang**,

(57) **CLAIM**

The ornamental design for a lamp housing, as shown and described.

DESCRIPTION

FIG. 1 is a front view of the lamp housing according to a first embodiment of the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front view of the lamp housing according to a second embodiment of the new design;

FIG. 8 is a back view thereof;

FIG. 9 is a left side view thereof;

FIG. 10 is a right side view thereof;

FIG. 11 is a top view thereof; and,

FIG. 12 is a bottom view thereof.

The broken lines depict portions of the lamp housing that form no part of the claimed design.

1 Claim, 2 Drawing Sheets
